UNITED STATES PATENT OFFICE.

DAVID TRUE, OF SALISBURY, MASSACHUSETTS.

CARRIAGE-WRENCH.

SPECIFICATION forming part of Letters Patent No. 292,186, dated January 22, 1884.

Application filed July 23, 1883. (No model.)

To all whom it may concern:

Be it known that I, DAVID TRUE, of Salisbury, in the county of Essex and State of Massachusetts, have invented new and useful Improvements in Carriage-Wrenches, of which the following is a specification.

In the accompanying drawings, in which similar letters of reference indicate like parts, Figure 1 is a perspective view of a wrench embodying my invention. Fig. 2 is a longitudinal section of the same. Fig. 3 is a view of the socket or box detached.

A is a bar, provided on its face with the central circular flange, A', and at its ends with the balls or weights A''. This bar A is provided with a central opening, by means of which it may be rotated on the handle B, which is provided with a ferrule, b, of metallic substance, such ferrule forming a bearing for the bar A. The bar is prevented from becoming detached from the handle by means of the screw b'. Thus far there is nothing novel in the device.

C is the socket or box for grasping the nut, secured to or projecting from the base or back D. Pins a, projecting from the bar A into corresponding openings in the back D, cause it to partake of any rotary motion imparted to the bar.

What remains, and in what my invention consists, is means for preventing the socket from dropping from the bar. I accomplish my object—viz., the holding of the socket-back D in place against the face of the bar A and within the flange A'—by cutting an annular groove, D', in the periphery of the circular base D, and placing in such groove a ring, E, made of rubber or other elastic or contractile substance or composition of matter, such ring being thick enough to extend slightly beyond the mouth of the groove, and sufficiently to press against the inside surface of the flange A'. By means of the friction thus produced the back and socket D C are held against the bar A, allowing the pins a to remain in engagement.

The groove D' may be rectangular or of any shape, but is shown in the drawings as dovetailed, the better to hold the ring E, fitting into it. Sufficient depth is necessary to prevent the ring from rolling over and out.

50

The wrench thus produced may be used in connection with carriage-nuts, or elsewhere, as deemed desirable.

In operation, the socket C is placed over the nut, the handle B held firmly in the hand, 55 and the bar rotated on the handle.

The socket is easily removable, and others of different sizes and shapes may be readily applied.

If desired, the flange A' and back D may be 60 of a corresponding shape other than circular, in which case the pins a will not be needed to communicate the rotation.

Having thus fully described my invention, what I claim, and desire to secure by Letters 65 Patent, is—

1. In a wrench, the combination, with the bar A, or portion adapted to be rotated by the user, provided with the flange A', of the socket or portion applied to the nut, said 70 socket being provided with the back or base D, which is provided with the groove D', and the elastic ring E, resting in said groove and compressed against the inner surface of said flange, substantially as and for the purpose set forth.

2. In a wrench, the combination of the following elements, viz: the socket or portion adapted to be applied to the nut, the bar or portion adapted to rotate the socket, and an 80 intermediate elastic substance arranged and applied to hold the said socket and bar together by its own elasticity and friction, substantially as and for the purpose hereinbefore set forth.

DAVID TRUE.
